UNITED STATES PATENT OFFICE

154,641

DESIGN FOR A FINGER RING

Norman R. Schrager, Beverly Hills, Calif.

Application July 6, 1948, Serial No. 147,407

Term of patent 3½ years

(Cl. D45—10)

To all whom it may concern:

Be it known that I, Norman R. Schrager, a citizen of the United States, residing in the city of Beverly Hills, county of Los Angeles, and State of California, have invented a new, original, and ornamental Design for a Finger Ring, of which the following is a specification, reference being had to the accompanying drawing, forming a part thereof.

Fig. 1 is a perspective view of the finger ring, showing my new design, as viewed from the top and one end and one side thereof, and Fig. 2 is a perspective view of the finger ring, showing the bottom, the other side and the other end thereof.

I claim:

The ornamental design for a finger ring, as shown and described.

NORMAN R. SCHRAGER.
